STANLEY MACOMBER, OF MASSILLON, OHIO.

MACHINE FOR ASSEMBLING STEEL STRUCTURAL UNITS.

Application filed May 11, 1925. Serial No. 29,353.

The present improved machine is designed more particularly for use in assembling the component parts of steel structural units of a truss section for buildings and the like, where such unit is mainly fabricated from a plurality of bar or rod-like elements. Thus, in the illustrative unit to which reference will hereinafter be made, straight rods are employed for the top and bottom chords, respectively, while the web member of the truss is in the form of another rod or bar that is bent reversely to form a succession of oppositely directed V's, the angles of which lie between the bars thus constituting the upper and lower chords. The several bars are preferably electrically welded together at the points where the angles of such web member thus contact with the chord members and, in addition, reinforcing plates are similarly welded to the ends.

The object of the present improvements is to provide a simple and conveniently operable mechanism for receiving and holding such component parts of a structural unit of the type in question so that the welding together of such parts may be accomplished expeditiously and with accuracy. A further object is to avoid distortion or bending of the component parts since this results in the production of a crooked product.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a plan view of the present improved mechanism with the component parts of a structural unit of the type in hand secured in place therein; Fig. 2 is a similar plan view of the bed plate of such mechanism stripped of other parts; Figs. 3, 4 and 5 are vertical transverse sections of the mechanism taken on the planes indicated by the lines 3—3, 4—4 and 5—5, respectively, Fig. 1; Figs. 6 and 7 are similar sections of a detail, the plane of the section being indicated by the line 6—6, Fig. 1, and the detail being shown in two different operative positions; and Fig. 8 is a perspective view on a reduced scale of one end of a structural unit

of the sort intended to be assembled by the mechanism.

For an understanding of the construction and operation of the mechanism, reference may be had first of all to the form of such structural unit as thus illustrated in Fig. 8. Such unit, as previously explained, is in the form of a truss suitable for use as a beam in carrying light loads as in the case of joists in floors and the like, although the utility of such unit is not limited to any such particular field or for that matter to any particular type of structural unit.

The latter, it will be noted, is made up of five principal elements or pieces, viz, two straight bars or rods 1 that compose the upper chord; two similar bars or rods 2 that compose the bottom chord, such last mentioned rods or bars being straight throughout the major portion of their length but having their ends bent up to form angularly related portions 2^a that terminate in portions 2^b lying parallel with the corresponding ends of upper chord members 1; and another rod or bar 3 that constitutes the web member of the structure, said member, as hereinbefore indicated, being bent reversely to form a succession of oppositely directed V's, the angles 3^a of which lie between the upper pair of bars 1 and the lower pair of bars 2.

For the purpose of developing enough strength in the truss end, when resting on the support therefor provided to carry the load of the truss, reinforcing elements are included in such end. In the construction illustrated, these comprise two plates, one a horizontal plate 5 disposed directly beneath the horizontally extending portions 2^b of the lower chord members, and the other 95 a vertical plate 6 that rests with its lower edge on such horizontal plate and extends inwardly longitudinally of the structure to the first upwardly bent angle 3^a of the web member 3. When suitably welded together 100 these two plates, it will be seen, constitute in effect an inverted T-bar in cross section.

The preferred method of securing the various component members of the structure together is to weld together the rods or bars 105 that enter into the top and bottom chords respectively and the web member at the points where they intersect, and similarly to weld such bars to the plates that constitute the end reinforcement of the structure and 110 to weld such plates to each other.

Just as in Fig. 8 only one end portion of

- the structural unit is shown, so the illustration in Figs. 1 and 2 is limited to the corresponding end portion of the assembling mechanism. It will be understood, of course, that the length of such mechanism will vary, depending upon the length of the structural unit that is to be made thereon. The base of the mechanism proper is a horizontally extending plate 10 of substantial thickness 10 that is supported on a heavy I-beam 11 (see Figs. 3, 4 and 5) or like solid foundation. One edge of the plate is preferably flush with such support, while the other projects therebeyond so as to lie clear of the same, 15 and a plank 12 or equivalent layer of solid resistant heat insulating material is interposed between the plate 10 and the support 11.
- Fixedly mounted on the plate 10, adjacent 20 its edge which thus lies flush with the support, is a longitudinally extending angle bar 13 against which the rods 2 that compose the bottom chord of the structural unit are designed to be placed in the course of assembly. 25 At spaced points corresponding with the points where the angles 3^a of the web member 3 lie between the paired bars 2, said plate is formed with openings 10^a for the spray from the welding operation to escape. 30 Hingedly attached to the opposite or overhanging edge of the plate is a second longitudinally extending angle bar 14, the hinges comprising longitudinally spaced brackets 15 on the underside of a bar that are pivotally attached to downwardly projecting lugs 15^a on such overhanging portion of plate 10 (see Fig. 3). When bar 14 is in its raised position, the rods 1 that constitute the upper chord member of the structural 40 unit will be assembled against the vertical flange of this bar 14 and such flange, together with the opposed flange of bar 13, serve equally to hold in place the angles 3^a of the web member 3.
- 45 In order to retain angle bar 14 in its operative raised position, one or more swinging handled locks 16 are provided, as shown in Figs. 6 and 7, such locks being pivotally attached to the underside of the overhanging portion of bed 10 intermediately of the locks 16 to which the bar is pivotally attached in the manner just described. When swung outwardly, as shown in Fig. 6, these locks provide a rigid support for the bar 14, but 50 when swung into parallel relation with the bed, the bar is left free to drop down out of the way, thus facilitating the removal of the finished structural unit.
- In addition to bars 13 and 14, which support the outwardly directed faces of the chord and web members entering into the structural unit, a series of vertical posts 17 are provided adjacent the overhanging edge of plate 10, just sufficient space being left 55 between such posts and the vertical flange

of bar 14, when the latter is in its raised position, to receive the bars 1, as shown in Fig. 3, and pivotally attached to corresponding posts 18, mounted upon or adjacent to angle bar 13, are clamps 19 of the form likewise best shown in Fig. 3. Each such clamp, it will be noted, comprises adjacent its inner or pivotally attached end an offset portion 19^a that is adapted to engage the inner faces of rods 2 when the latter are assembled 70 against the vertical flange of angle bar 13, the outer end of each clamp being formed with a handle 21, for convenience in operating the same, and adjacent such handle end with a vertical slot 22 that is adapted to fit over the corresponding post 17. The latter, it will be noted, is formed with an opening 23 through which a keeper in the form of a pin (not shown) may be inserted to hold the clamp in its lowered or operative 80 position.

To accommodate the reinforcing plates that enter into the construction of the end of the unit, the corresponding overhanging portion of plate 10 is cut away, as shown in 90 the upper right-hand corner of Figs. 1 and 2, and a supplemental plate 25 secured to said plate 10 by means of splice plates 26 so as to provide a shelf on a somewhat lower plane. The hingedly mounted angle bar 14 terminates short of this portion of the bed and instead thereof, a short angle bar 27 that faces in the same direction as bar 13 is mounted on bed 10 adjacent such cut-back portion. Plate 25 is provided with openings 100 28 for the weld spray and between its inner edge and the opposed edge of plate 10 blocks 29 are supported on splice plates 26, such blocks having their upper faces notched to support in proper relative positions the two 105 reinforcing plates 5 and 6 and the corresponding ends of top chord members 1 and end portions 2^b of the bottom chords 2; it being noted that the two clamps 30 adjacent 110 this portion of the bed, such clamps otherwise corresponding with previously described clamps 19, instead of being provided with offset portions 19^a and 19^b are formed on their under faces with portions 30^a and 30^b that complement said blocks and assist 115 in thus retaining in place the parts of the structural unit in question.

Still a third modified form of clamp 35 is provided between the last of clamps 19 and the first of said clamps 30, such clamp 35, as shown in Fig. 4, having offset portions 35^a and 35^b specially designed to co-operate with the component elements of the structural unit at this point.

The operation of the mechanism as a whole 125 may now be briefly indicated. The several clamps 19, 30 and 35 being thrown back and angle bar 14 dropped out of the way, the preformed chord and web components of the structural unit may be easily and quickly 130

placed in position on the bed 10, their proper location being facilitated by the fixed bar 13, the posts 17 and the short fixed bar 27, taken in conjunction with blocks 29. The front 5 angle bar 14 is thereupon swung and locked in place and the several clamps brought down and secured to their respective posts. The welding operation is then proceeded with in the manner hereinbefore sufficiently set forth. 10 As soon as the bars and reinforcing plates have thus been united at the proper points, the clamps are thrown back, the bar 14 again dropped out of the way and the finished structural unit lifted off. 15 By reason of the insulating board 12, which is interposed between plate 10 and support 11, the transfer of heat to the latter such as might cause even a heavy I-beam to bend is so reduced as to maintain the bed at 20 all times flat and thus permit of the accurate assembly of the parts composing the structural unit. The production of crooked units or joists is thus avoided. At the same time the arrangement of the clamps is such as to 25 facilitate not only the assembly of the component rods and reinforcing plates, but also the removal of the finished article therefrom.

Other modes of applying the principle of my invention may be employed instead of 30 the one explained, change being made as regards the mechanism herein disclosed, provided the means stated by any of the following claims or the equivalent of such stated means be employed.

35 I therefore particularly point out and distinctly claim as my invention:—

1. In mechanism for assembling welded-together structural units of the type described, the combination of a bed plate; a 40 support therefor; a fixed, upwardly projecting flange adjacent one edge of said plate; and a corresponding flange adjacent the other edge of said plate, said last-named flange being hingedly attached to said plate 45 so as to be movable to a position clear of its upper face.

2. In mechanism for assembling welded-together structural units of the type described, the combination of a bed plate; a 50 support therefor; a fixed, upwardly projecting flange adjacent one edge of said plate; a corresponding flange adjacent the other edge of said plate, said last-named flange being hingedly attached to said plate so as to be 55 movable to a position clear of its upper face; and means adapted to retain said last-named flange in operative position.

3. In mechanism for assembling welded-together structural units of the type described, the combination of a bed plate; a 60 support therefor; a fixed upwardly projecting flange adjacent one edge of said plate; a corresponding, movable flange adjacent the other edge of said plate; and transversely disposed clamps pivotally attached to said 65

plate adjacent said first-named flange and adapted to co-operate with said flanges to retain the component parts of such unit in proper position therebetween.

4. In mechanism for assembling welded-together structural units of the type described, the combination of a bed plate; a support therefor; a fixed, upwardly projecting flange adjacent one edge of said plate; a corresponding, movable flange adjacent the other edge of said plate; transversely disposed clamps pivotally attached to said plate adjacent said first-named flange and adapted to co-operate with said flanges to retain the component parts of such unit in proper position therebetween; and means adapted to lock said clamps in operative position. 70 75 80

5. In mechanism for assembling welded-together structural units of the type described, the combination of a bed plate; a support therefor; a fixed, upwardly projecting flange adjacent one edge of said plate; a corresponding, movable flange adjacent the other edge of said plate; transversely disposed clamps pivotally attached to said plate adjacent said first-named flange and adapted to co-operate with said flanges to retain the component parts of such unit in proper position therebetween; said clamps having off-set portions adapted directly to 90 engage with such parts. 95

6. In mechanism for assembling welded-together structural units of the type described, the combination of a bed plate; a support therefor; an angle-bar fixed to said 100 plate adjacent one edge thereof with one flange directed upwardly and facing towards the opposite edge of said plate; a corresponding, but reversely facing angle-bar adjacent the opposite edge of said plate; and hinges 105 pivotally securing said last-named bar to said plate, said hinges being located so as to leave the upper face of said plate clear. 110

7. In mechanism for assembling welded-together structural units of the type described, the combination of a bed plate; a support therefor; an angle-bar fixed to said 115 plate adjacent one edge thereof with one flange directed upwardly and facing towards the opposite edge of said plate; a corresponding, but reversely facing angle-bar adjacent the opposite edge of said plate; hinges pivotally securing said last-named bar to said plate, said hinges being located so as to leave the upper face of said plate clear; 120 and keepers for retaining said last-named bar in operative position, said keepers being pivotally attached to the under side of said plate. 125

8. In mechanism for assembling welded-together structural units of the type described, the combination of a bed plate; a support therefor; an angle-bar fixed to said 130 plate adjacent one edge thereof with one flange directed upwardly and facing towards

- the opposite edge of said plate; a corresponding but reversely facing angle-bar adjacent the opposite edge of said plate; hinges pivotally securing said last-named bar to 5 said plate, said hinges being located so as to leave the upper face of said plate clear; and transversely disposed clamps pivotally attached to said plate adjacent said first-named bar and adapted to cooperate therewith 10 and with said last-named bar to retain the component parts of such unit in proper position therebetween, said clamps having off-set portions adapted directly to engage with such parts.
- 15 9. In mechanism for assembling welded-together structural units of the type described, the combination of a bed plate; a support therefor; an angle-bar fixed to said plate adjacent one edge thereof with one 20 flange directed upwardly and facing towards the opposite edge of said plate; a corresponding, but reversely facing angle-bar adjacent the opposite edge of said plate; hinges pivotally securing said last-named 25 bar to said plate, said hinges being located so as to leave the upper face of said plate clear; transversely disposed clamps pivotally attached to said plate adjacent said first-named bar and adapted to cooperate therewith 30 and with said last-named bar to retain the component parts of such unit in proper position therebetween, said clamps having off-set portions adapted directly to engage with such parts; and posts rising from said plate in alignment with said clamps, respectively, said clamps being slotted to receive said posts.
- proper position therebetween, said clamps having off-set portions adapted directly to engage with such parts; and blocks on said plate complementary to such off-set clamp 35 portions.
10. In mechanism for assembling welded-together structural units of the type described, the combination of a bed plate; a support therefor; an angle-bar fixed to said plate adjacent one edge thereof with one flange directed upwardly and facing towards the opposite edge of said plate; a corresponding, but reversely facing angle-bar adjacent the opposite edge of said plate; 40 hinges pivotally securing said last-named bar to said plate, said hinges being located so as to leave the upper face of said plate clear; transversely disposed clamps pivotally attached to said plate adjacent said first-named bar and adapted to cooperate therewith and with said last-named bar to retain the component parts of such unit in proper position therebetween, said clamps having off-set portions adapted directly to engage 45 with such parts; and posts rising from said plate in alignment with said clamps, respectively, said clamps being slotted to receive said posts.

Signed by me this 24 day of April, 1925.

STANLEY MACOMBER.
